UNITED STATES PATENT OFFICE.

ARTEMUS CALVIN BROWN, OF SALISBURY, MARYLAND.

MITER-BOX.

1,123,235.

Specification of Letters Patent.

Patented Jan. 5, 1915.

Application filed February 6, 1912. Serial No. 675,781.

To all whom it may concern:

Be it known that I, ARTEMUS C. BROWN, a citizen of the United States, residing at Salisbury, in the county of Wicomico and State of Maryland, have invented a new and useful Miter-Box, of which the following is a specification.

This invention relates to combination tools, and has for its primary object to provide a novel adjustable miter machine for saws.

This invention also contemplates a tool of this character which shall be simple, light and compact in construction, which may be folded to be readily carried in the pocket, and which shall be convenient and efficient in use.

To the above and other ends, this invention is characterized by the novel construction and combination of parts hereinafter elicited and pointed out in the appended claim, it being understood that the device is susceptible of deviations or alterations in its details within the scope of the appended claim without departing from the spirit of the invention.

The preferred embodiments of the invention are illustrated in the accompanying drawings, wherein similar reference characters indicate similar parts, and wherein:—

Figure 1 is a perspective view of the tool as used as a miter machine for saws. Fig. 2 is an elevation thereof. Fig. 3 is a fragmental detail in plan view of the body of the tool. Fig. 4 is a section on the line 5—5 of Fig. 2 on an enlarged scale. Fig. 5 is a perspective of a detail. Fig. 6 is a perspective view of a modified form. Fig. 7 is an elevation thereof, parts broken away. Fig. 8 is an elevation from the side thereof, parts broken away and the parts being in a different position. Fig. 9 is a fragmental detail in elevation of the modified form when folded.

Referring in detail to the drawings, 15 designates the body or stock of the tool, which is preferably of sheet metal or cast metal, and which has the edges thereof converging toward the outer end, one edge 50 forming a straight edge 25 which bears suitable graduations and the other edge having a depending flange 42. A semi-circular adjusting plate 19 is pivoted to the inner end of the body 15 by means of a pin 20 passing through the adjusting plate 19 and through the aperture 45 in the inner end

of the body 15. The adjusting plate 19 and the body 15 are provided with the respective registering arcuate slots 21 and 46 which are concentric with the axis of the pivotal point, and a clamping bolt 22 passes through the slots 46 and 21 and bears a jam nut 23 adapted to clamp the adjusting plate 19 firmly against the body 15 at any adjustment. The plate 19 is provided with 60 a plurality of pointers 24 projecting from the convex or arcuate side thereof, which pointers co-act or coöperate with the scale of protractor graduations 47 on the body 15 to indicate the angle at which the plate 19 is set relative to the body 15 and thereby 65 permitting the plate 19 to be set at any desired angle relative to the said body. A hinge plate 18 is hinged at one edge to the straight edge or side of the plate 19 and 70 is adapted to normally seat or bear against the inner end 44 of the body 15 to lie in the plane of the plate 19. A blade 16 is hinged to the plate 18, the axes of the hinges being parallel, and this blade 16 has the 75 edges thereof converging toward its outer or free end, one of the edges 33 forming a straight edge which bears suitable graduations coöperating with the graduated straight edge 25 of the body 15 when the 80 body and blade are swung into alignment to form a continuous straight edge and ruler. A flange 17 projects from the other edge of the blade 16 and is provided with an elongated longitudinal slot 43 having a 85 suitable scale of graduations 48 along one edge thereof on the outer side of the flange for indicating various degrees of the blade 16 relative to the plate 19 and a scale of linear graduations 48' along the other edge 90 thereof.

The link 27 is pivoted at one end to an ear 26 secured to and projecting from the plate 19, and at its other end is engaged over the inner end of a bolt 28 which passes loosely 95 through the slot 43 and bears a jam nut 29 on its outer end to clamp the flange 17 between the link 27 and the jam nut 29 to retain the plate 19 and the blade 16 in any adjusted position to which they are set relative 100 to each other. A washer 30 is interposed between the jam nut 29 and the flange 17 on the bolt 28 and this washer 30 is provided with a tail piece 30' which has an intermediate crimped portion 31 snugly and slidably entering the slot 43 and has the double pointer or straight edge 32 at its outer or

free end, the said pointer or straight edge 32 overlapping the edges of the slot 43 and co-acting or coöperating with the graduations 48 and 48' on the outer face of the flange 17 along the edges of the said slot to indicate the angle of the blade 16 relative to the plate 19 on the graduations 48, thereby permitting the blade 16 to be set at any desired angle relative to the said plate 19. It is to be observed that the crimped portion 31 which snugly enters the slot 43 will have two points of contact with each edge of the slot so that the crimped portion serve as a slide movable in the slot, and also permits the bolt 28 to be out of engagement with the edges of the slot 43 so that the threads of the bolt will not be injured. An auxiliary blade 34 which corresponds in contour to the blade 16 is hinged at its smaller end to the outer or free end of the blade 16 as designated by the numeral 39, and this auxiliary blade 34 is adapted to swing into a close parallel and coinciding relation with the blade 16, forming therewith a guide for handsaws. A shim plate 36 is secured to the inner end of the auxiliary blade 34 and when the blades 16 and 34 are swung together said shim plate 36 is adapted to be sandwiched between the ends of the said blades to retain the blades in parallel relation.

The blade 16 is provided with a tap 37 at its outer or free end which is adapted to coincide or register with an aperture 49 in the auxiliary blade 34 and shim plate 36, whereby when the blades 16 and 34 are swung together or folded, a thumb screw 38 may be passed through the aperture 49 and engaged in the tap 37 to retain the blades in that relation to form the saw guide. The body 15 is provided with a pricker 41 at its outer end, and the auxiliary blade 34 is provided with a coöperating pricker 40 projecting from the inner end thereof, the said pricker 40 forming a stop adapted to strike the blade 16 when the blades are opened or swung into alinement to prevent the excessive movement of the blades 16 and 34 relative to each other. The graduations 48' indicate the distances between the prickers as they are swung relative to each other, thereby permitting the prickers to be set at any desired distance from each other.

The auxiliary blade 34 has a graduated straight edge 35 which coöperates with the graduated straight edge 33 of the blade 16 when the blades are swung into alinement.

In the form shown in Figs. 6 to 9, inclusive, the blade 16 is connected to the plate 19 by means of a hinge, the leaves of which are bent similarly into obtuse angles to provide the respective outer and inner sections 18^a—18^d and 18^b—18^c. The outer sections 18^a—18^d are secured respectively to the plate 19 and the inner end of the blade 16. This

hinge permits the body 15 and the blade 16 to be swung into alinement, the link 27 swinging over the end of the hinge and brings the said body and blade into a parallel spaced relation when the said parts are folded one upon the other, whereby the tool may be compactly folded. This hinge is substituted in lieu of the hinge plate 18 of the former construction, which hinge plate permits the blade and body of the former construction to fold into a spaced parallel relation, thus to allow the clamping bolt 22 and its nut 23 as well as the adjusting link 27 and the parts coöperating therewith, to be housed between the stock and the saw guide made up of the blades 16 and 34. This hinge plate 18 rests upon one end of the stock 15 while the device is in use and is thus held in alinement with the adjusting plate 19, at the same time supporting the saw guide beyond the end of the stock so that said saw guide can be adjusted to form either an acute or an obtuse angle with the top of the stock.

When used as a miter machine for saws, the blades 16 and 34 are retained in folded parallel relation by the thumb screw 38 to form the saw guide and the saw guide is then set at the desired angle relative to the body 15 by swinging the plate 19 upon the body 15 and by swinging the blade 16 relative to the plate 19, the various angles being indicated by the graduations 47 and 48, respectively. In the first form the axis of the hinged connection between the blade 16 and the hinge plate 18 lies in a plane at right angles to the plane of the axis of the pivotal point between the plate 19 and the body 15, whereby the blade 16 swings to and from the axis of the pivotal point of the plate 19 and the body 15, and in the second form, the axis of the hinged connection between the deflected portions 18^a and 18^b of the hinge leaves lies in a plane at right angles to the plane of the axis of the pivotal point between the plate 19 and the body 15, and by the foregoing adjustment, the saw guide may be set at any desired angle relative to the body 15. Then by applying the body 15 to the object to be sawed, this guide is positioned at the desired angle relative to the body, whereby, when the saw is inserted into the saw guide the desired cut into the object may be made.

When used as a pair of dividers and compass, the body 15 and blade 16 are swung relative to each other, as more clearly shown in dotted lines in Fig. 2, whereby the pricklers 40 and 41 may be brought into operation for that purpose as will be readily understood. The graduations 48' indicate the distances between the pricklers 40 and 41

carried by the saw guide, and the body, respectively, and in this manner the said prickers may be set at any desired distance apart for use as a pair of dividers or a compass.

When the device is employed as a miter or bevel square, the blade 16 is swung into the plane of the stock or body 15 and at right angles thereto, the inner end of the 10 blade 16 being straight and being adapted to swing flatly against the straight edge 25 so as to lock the blade and stock against swinging in the plane in which they both lie. The inner end of the blade 16 is 15 straight in order that it may swing flatly against the straight edge 25, the hinged connection between the blade 16 and the plate 19 permitting the inner end of the blade 16 to swing against the straight edge 25, but 20 normally the ends of the blade and stock part. By removing the thumb screw 38 the body 15, blade 16, and the auxiliary blade 34 may be swung into alinement, whereby 25 the respective graduated straight edges 25, 33 and 35 fall into alinement to coöperate with each other to form a continuous straight edge and ruler. This tool will also be found useful for various other purposes which will be apparent.

70 In this manner it will be seen that the present invention provides for a combination tool embodying a novel adjustable miter machine, in connection with a ruler,

square, bevel or miter square, divider and compass, the tool being adapted to fold 35 compactly to be carried in the pocket, and being simple and light in construction, and being convenient and efficient in use.

Having described the invention, what is 40 claimed as new is:

The combination with an adjusting plate and a saw guide, of a hinge plate connecting the adjusting plate and the saw guide, a stock extending under and swiveled to the adjusting plate and adapted to project 45 at one end under the hinge plate to hold the plates in alinement, said saw guide being adjustable angularly to form acute or obtuse angles with the top of the stock, binding means upstanding from the stock and 50 adjusting plate, and adjusting means connecting the saw guide and adjusting plate, said saw guide and stock being foldable into parallel relation, the hinge plate constituting means for spacing the saw guide 55 and stock when folded, thereby to permit housing of the clamping and adjusting means between the stock and guide.

In testimony that I claim the foregoing as my own, I have hereto affixed my signature 60 in the presence of two witnesses.

ARTEMUS CALVIN BROWN.
